UNITED STATES PATENT OFFICE.

HARRY STILLSON HART AND OTTO W. MEISSNER, OF CHICAGO, ILLINOIS,
ASSIGNORS TO THE RODGER BALLAST CAR COMPANY, OF CHICAGO,
ILLINOIS, A CORPORATION OF ILLINOIS.

DUMP-CAR.

SPECIFICATION forming part of Letters Patent No. 761,674, dated June 7, 1904.

Application filed January 30, 1903. Serial No. 141,147. (No model.)

To all whom it may concern:

Be it known that we, HARRY STILLSON HART and OTTO W. MEISSNER, citizens of the United States, residing at Chicago, in the county of 5 Cook and State of Illinois, have invented certain new and useful Improvements in Dump-Cars, of which the following is a specification.

The invention relates principally to that class of dump-cars which is provided with 10 dumping-hopper bottom portions, commonly called "Rodger" dumping-cars, which dump ballast between the tracks in a typical manner, and particularly to the means by which a maximum opening may be provided for the dis- 15 charge of material other than ballast, such as coal and the like.

The invention has further reference to the means for opening and closing the discharging mechanisms and holding them in opera- 20 tive closed position, all of which will more fully hereinafter appear.

The principal object of the invention is to provide a simple, economical, and efficient hopper-bottom dumping-car with discharging 25 mechanism by which a maximum opening may be provided.

A further object of the invention is to provide a hopper-bottom dumping-car with means by which the discharging mechanism may be 30 closed by and during the same operation and held in closed operative position, all of which will more fully hereinafter appear.

The invention consists principally in a hopper-bottom dumping-car in which there are 35 combined a supporting-frame portion, a V-shaped hopper portion extending longitudinally of the car with its apex arranged below the underframing and at or near the longitudinal center thereof, the inclined side portions of which are provided with lower swing- 40 ing portions forming a part thereof, and means for closing such swinging portions successively, first one and then the other, by and during one and the same operation, substan- 45 tially as hereinafter set forth.

The invention consists, further, in a hopper- bottom dumping-car in which there are com- 95 bined a supporting-framework, a V-shaped

hopper portion extending longitudinally of the car with its apex arranged below the underframing and at or near the longitudinal center thereof and having inclined side portions which form the hopper proper and are divided into two portions, upper fixed portions secured to the frame of the car above 50 the underpinning and lower swinging portions secured to and extending below the underpinning of the car, and one of such swinging portions being heavier than the other, whereby the lighter one is closed first and 55 acts to limit and hold the second in position.

The invention consists further and finally in the features, combinations, and details of construction hereinafter described and claimed.

In the accompanying drawings, Figure 1 is 65 a cross-sectional elevation of a portion of a car as it appears when constructed in accordance with these improvements; Fig. 2, an enlarged plan view of a portion of one of the lower swinging sections of the hopper looking 70 at the same from below; Fig. 3, an enlarged perspective detail of the bolt and staple mechanism for locking and holding the swinging sections in closed position; and Fig. 4, an enlarged perspective view of one portion of the 75 lighter swinging section, showing the staple mechanism attached thereto.

In illustrating and describing these improvements we have only illustrated and described that which we consider to be new, 80 taken in connection with so much that is old as will properly disclose the invention and enable those skilled in the art to practice the same, leaving out of consideration other and well-known elements, which if shown and described herein would only tend to confusion, 85 prolixity, and ambiguity.

In constructing a car in accordance with these improvements we provide a supporting-framework having side sills *a* and intermediate sills *b* extending, as is usual, longitudinally of the car and tied together by any well-known means, and which is further provided with needle or deck beams *c*. To provide for carrying the load in the car we make a V- 95 shaped hopper portion and so arrange it that

it extends longitudinally of the car, with its apex arranged below the intermediate sills and at or near the longitudinal center thereof. This hopper portion proper is formed or 5 constructed so that it has two inclined side portions extending from a point at or near the upper outer sides of the car and inclined downwardly and inwardly until they meet at the apex, as above suggested, below the intermediate sills and at or near the longitudinal center of the car. Each of these inclined side portions is divided into two sections, an upper fixed section *s*, having its lower edges attached to the intermediate sills and arranged 10 above the same, and lower swinging sections *e* and *f* pivotally attached to the intermediate sills and below the same, so that they may both be opened and closed to provide for the discharge of material through a maximum opening, being the opening or space *g* directly between the intermediate sills, which opening permits of all kinds of material being discharged without any clogging or sticking. To provide for the opening and closing of 15 these swinging sections, one of such sections, preferably *e*, which is farthest removed from the closing mechanism, is made heavier than the section *f*, or, differently stated, the swinging section *f*, which is nearest to the closing mechanism, is made lighter than the farther swinging section *e*, so that by the closing mechanism hereinafter described the lighter swinging section *f* is first brought into position until it contacts the cleat or stop *h*, when 20 the heavier section is operated and swung into position until it also contacts a cleat or stop *i*, and both of such sections are positioned. To hold such parts in their closed and operative position, the lighter swinging section is provided with a plurality of staple-plates *j*, having perforations *k* therein, while the heavier swinging section is provided with a multiplicity of locking-bolts *l*, inclined at their lower ends and arranged to enter the 25 perforations in the staple-plates. This heavier swinging section is also provided with a rock-shaft *m*, having an operating-handle *n* thereon and connected with the locking-bolts by means of links *p*, so that as such rock-shaft 30 is rocked or vibrated the locking-bolts are either moved into engagement with the staples or extracted therefrom to permit of the desired operations. A locking-link *q* is provided and pivotally attached to the upper part of the heavier swinging section, so that it may engage the free upper end of the operating-handle and hold the parts in locked 35 position.

To move the doors into their operative position by and during one and the same operation, the lighter swinging section first and the heavier last, a second rock-shaft *r* is provided and movably mounted in the supporting-framework of the car. Secured to this rock-shaft are one or more chains *t*, which chains

are also secured to the lower end of the heavier swinging section. The lighter swinging section is provided with a bracket *u* for each chain at or near its lower free end, and such bracket is further provided with an idler-pulley *v*, directly contacting such chain, so as to minimize the frictional engagement therewith, all of the parts being arranged, as will be seen from an examination of the drawings, so that as the chain is tightened the lighter 75 section is first brought into position and then the heavier swinging section to enable it to be locked with the lighter section.

We claim—

1. In a hopper-bottom dumping-car of the 80 class described, the combination of a supporting-frame portion, a **V**-shaped portion extending longitudinally of the car with its apex arranged below the underpinning and at or near the longitudinal center thereof, the inclined 85 side portions of which are provided with lower swinging sections forming a part of each of the inclined sides of the car, and means for closing such swinging sections successively—first one and then the other—by and during 90 one and the same operation, substantially as described.

2. In a hopper-bottom dumping-car of the 95 class described, the combination of a supporting-framework, a **V**-shaped hopper portion 100 extending longitudinally of the car with its apex arranged below the underpinning and at or near the longitudinal center thereof and having inclined side portions which form the hopper proper and are divided into two sections—upper fixed sections secured to the frame of the car above the underpinning and lower swinging sections secured to and extending below such underpinning of the car and one of such swinging sections being heavier 105 than the other, whereby the lighter swinging section is closed first and acts to limit and hold the second in position, substantially as described.

3. In a hopper-bottom dumping-car of the 110 class described, the combination of a supporting-framework, a **V**-shaped hopper portion extending longitudinally of the car with its apex arranged below the underpinning and at or near the longitudinal center thereof and having inclined side portions divided into two sections—upper fixed sections secured to the framework of the car above the underpinning and lower swinging sections pivotally secured to the framework of the car below the underpinning, one of such swinging sections being lighter than the other, whereby it is closed first and acts to limit the movements of the second, a single rock-shaft, chain mechanism secured thereto and to the heavier lower swinging section and contacting the lighter so that the lighter swinging section is first closed and acts to limit or hold the second and heavier swinging section in position, substantially as described.

shaft arranged in the framework of the car, and chain mechanism secured to the second rock-shaft and to the heavier swinging section of the hopper and contacting the lighter 5 swinging section to close both of such sections by and during one and the same operation, substantially as described.

10. In a hopper-bottom dumping-car of the class described, the combination of supporting- 10 framework, a V-shaped hopper portion the inclined sides of which are provided with lower swinging sections—one on each inclined side, and mechanism for locking both of such swinging sections together at or near their intersecting 15 points, substantially as described.

11. In a hopper-bottom dumping-car of the class described, the combination of a supporting-framework having intermediate sills, a V- 20 shaped hopper portion extending longitudinally of the car with its apex at or near the longitudinal center thereof below the intermediate sills and having inclined side portions provided with two lower swinging sections on 25 each inclined side, stop mechanism for limiting the inward movement of the swinging sections, and mechanism for locking both of such swinging sections together at or near their intersecting points, substantially as described.

12. In a hopper-bottom dumping-car of the 30 class described, the combination of a supporting-framework, a V-shaped hopper portion extending longitudinally of the car with its apex arranged below the underpinning and at

or near the longitudinal center thereof and having inclined sides, each of which is provided with a lower swinging section, stop mechanism for limiting the inward movement of the lower swinging sections, a rock-shaft, chain mechanism for closing such swinging sections, and bolt and staple mechanism on 35 such swinging sections for locking the same together at or near their intersecting points, substantially as described.

13. In a hopper-bottom dumping-car of the class described, the combination of a supporting- 40 framework, a V-shaped hopper portion extending longitudinally of the car with its apex arranged below the underpinning and at or near the longitudinal center thereof and having inclined sides, each of which is provided with lower swinging sections, a single rock-shaft, chain mechanism secured to such rock-shaft and to one of such swinging sections and contacting the other swinging section for moving both of such sections by and 45 during the same operation of the rock-shaft, staple mechanism on one of such swinging sections, bolt mechanism on the other swinging section, and a rock-shaft for operating the bolt mechanism, substantially as described. 50
